UNITED STATES PATENT OFFICE.

JOHN F. O'CONNOR, OF CHICAGO, ILLINOIS, ASSIGNOR TO WILLIAM H. MINER, OF CHAZY, NEW YORK.

SIDE BEARING.

1,357,811.

Specification of Letters Patent.

Patented Nov. 2, 1920.

Application filed September 25, 1919. Serial No. 326,123.

To all whom it may concern:

Be it known that I, JOHN F. O'CONNOR, a citizen of the United States, residing at Chicago, in the county of Cook and State 5 of Illinois, have invented a certain new and useful Improvement in Side Bearings, of which the following is a full, clear, concise, and exact description, reference being had to the accompanying drawings, forming a 10 part of this specification.

This invention relates to improvements in side bearings.

One object of the invention is to provide a simple and efficient side bearing for rail- 15 way cars, which is self-centering, non-shift- able, and relatively inexpensive to man- ufacture.

The invention furthermore consists in the improvement in the parts and devices and 20 in the novel combination of the parts and devices herein shown, described and made the subject matter of the claims.

In the drawing forming a part of this specification, Figure 1 is a view partly in ele- 25 vation and partly in section of portions of body and truck bolsters of a railway car showing my improvements in connection therewith. Fig. 2 is a top plan view of the construction shown in Fig. 1. And Fig. 3 is a vertical sectional view taken substan- 30 tially on the line 3—3 of Fig. 1. In Fig. 2 parts of the base casting are broken away in order to permit all three figures being shown on the same sheet.

In said drawing, 10 denotes the upper 5 part of a truck bolster and 11 the under part of an opposed body bolster. The improved bearing is shown as secured to the truck bolster and comprises, broadly, a housing or 0 retaining member, or base casting A, and an anti-friction element B.

The housing A is provided with a pair of spaced side walls 12—12 and rounded integral end walls 13—13. At its bottom, the 5 housing A is provided with perforated corner lugs indicated at 14 by which it is adapted to be riveted or otherwise rigidly secured to the bolster. The bottom wall provides a flat horizontal bearing surface as 0 indicated at 15 for the anti-friction element.

The anti-friction element B, as shown, is of cylindrical outline and consists of an upper section 16 and lower section 17. The two sections 16 and 17 are rigidly united

preferably by a mortise and tenon joint, the 55 tenon 18 being formed integral with the section 17 and mortised into a suitable socket 19 in the section 16. The tenon 18 is made sufficiently long so that it extends into a longitudinally arranged opening 20 60 provided in the section 16 and the parts are held assembled by a cotter 21 extended through the tenon 18 in the manner most clearly shown in Fig. 3.

In a side bearing of the type disclosed, it 65 is of course essential that the anti-friction element return to its central normal position after each actuation. It is also ex- tremely desirable that the anti-friction ele- 70 ment be prevented from bodily shifting 75 from vibration or other causes so that the anti-friction element will always be in con- dition to give full travel. I accomplish the results mentioned by the following means. The lower section 17 of the anti-friction ele- 80 ment is extended at its ends beyond the ends of the section 16, as indicated at 22—22. These end extensions 22 are received in openings 23—23 provided in the side walls 12. The end extensions 22 in outline, com- 85 prise an arcuate lower surface 24, an upper chord surface 25 the arc and the chord being united by curved surfaces 26 of relatively short radius. The outlines of the openings 23 are determined by the shape of the end 85 extensions 22 and are generated by the latter in such a way that the rounded ends defined by the curved surfaces 26 are always in contact with the two inclined surfaces 27—27 of the openings 23. In other words, the 90 surfaces 27 of the openings 23 in the housing are determined by rolling the anti-friction element to either side of normal and locating the varying positions of the curved portions 26 of the extension 22. When the 95 parts are constructed in this manner, it is evident that, while the anti-friction element is free to roll, it cannot be shifted bodily and hence cannot be displaced and will al- 100 ways be in a position to perform its full travel. The extended ends 22 of the lower section 17 also perform the additional function of weights or overbalances in returning the anti-friction element B to its normal po- 105 sition after each actuation upon release of the pressure. In this way, the use of all springs is avoided; the device is automatically self-centering under the influence of

gravity, and the anti-friction element cannot become displaced or shifted bodily without its being actually properly operated. By forming the anti-friction element in two parts as disclosed, I am able to readily assemble the parts since the lower section 17 may be placed within the housing lengthwise and then turned through an angle of 90° with the ends thereof in the openings 23 after which the top section 16 of the element B is applied and secured in place, the parts then being self-locked.

Although I have herein shown and described what I now consider the preferred manner of carrying out the invention, the same is merely illustrative and I contemplate all changes and modifications as come within the scope of the claims appended hereto.

20 I claim:

1. In an anti-friction bearing, the combination with a hollow retaining member having side walls, of an anti-friction element mounted therein, said element being formed 25 in an upper section and a lower separate section rigidly united, the lower one of said sections having its ends extended beyond the ends of the upper section, said retaining member having openings in said side walls thereof to accommodate said extended ends, the openings and extended ends being so formed as to prevent bodily shifting of the anti-friction element with respect to the retaining member.

35 2. In an anti-friction side bearing, the combination with a retaining member, of an anti-friction element mounted therein and adapted to roll back and forth, said element comprising upper and lower independently 40 formed sections, the lower section thereof being heavier than the upper section and constituting an overbalance to effect return

of the anti-friction element to normal under the influence of gravity.

3. In an anti-friction side bearing, the combination with a housing having side walls, said side walls being provided with openings therein, of an anti-friction element formed in two independent sections rigidly united, one of said sections having its ends 45 extended beyond the ends of the other section and overbalancing the latter, said extended ends working in said side wall openings and coöperating with the latter to prevent bodily shifting of the anti-friction element.

4. In a side bearing, the combination with a hollow housing having side walls provided with openings therein, of an anti-friction element having extensions on the ends thereof disposed within said openings, the outlines of said openings corresponding to the lines generated by said extensions as the element is moved to both sides of normal position, said extensions being always in contact with the edges of said opening to thereby prevent bodily shifting of the anti-friction element.

5. In an anti-friction bearing, the combination with a hollow base casting having 70 side walls provided with openings therein, of a substantially cylindrical roller disposed within said base casting, said roller being formed in two sections rigidly united, the lower section being extended at its ends beyond the other section, and into said openings and constituting an overbalance for the roller, said extended ends being always in contact with the edges of said recesses but permitting movement of the latter therein. 75

In witness that I claim the foregoing I have hereunto subscribed my name this 8th day of Sept. 1919.

JOHN F. O'CONNOR.
